FUEL OIL MEASURING MEANS WITH
DIPPING TRAP CHAMBER

Holden B. Townley, Cleveland Heights, Ohio, assignor to Perfection Stove Company, Cleveland, Ohio, a corporation of Ohio

Application October 2, 1944, Serial No. 556,681

7 Claims. (Cl. 222—356)

1

This invention pertains to liquid dispensing means, and it has to do more particularly with means for volumetrically feeding liquid. On this account, the invention is peculiarly suited to the feeding of liquid fuel to burners of the kind disclosed in Patent 2,247,689, dated July 1, 1941, wherein the desirability of feeding the fuel in measured quantities, especially for low or pilot fire purposes, is clearly set out.

Among the objects of the present invention is that of providing relatively simple and inexpensive, yet thoroughly reliable and durable means for intermittently feeding, at frequent enough intervals and in such manner that the supply to the burner is substantially constant, accurately measured small amounts of liquid fuel; and a further object is to provide an adjustment that is very convenient of access and manipulation for varying to a minute degree the quantity of fuel fed at each interval.

Although the invention was conceived and developed in connection with liquid fuel burning apparatus, it is to be understood that the same is not restricted to such an association. Two embodiments of the invention, which are intended as illustrative rather than as limiting, are shown in the accompanying drawings, and while I shall proceed to describe these embodiments in detail, I do not wish to be limited to the details thereof further than is required by the terms of the claims appended hereto.

Objects and advantages additional to those mentioned above will appear as I proceed to describe the invention by reference to the accompanying drawings wherein Fig. 1 is a sectional side elevation of liquid dispensing means incorporating the invention, the section being taken substantially on the line 1—1 of Fig. 2, said means being here employed as liquid fuel feeding means and the view including a fragment of a burner and a flow retarding means or coil in the connection between the dispensing means and burner; Fig. 2 is a plan view of the liquid dispensing means; Fig. 3 is a fragmentary end elevation of said means as though looking from the right of Fig. 1; Fig. 4 is a perspective view of the arm that supports the driving mechanism; Fig. 5 is a view, similar to but somewhat less comprehensive than Fig. 1, showing a modification of the liquid dispensing means; Fig. 6 is a horizontal section substantially on the line 6—6 of Fig. 5, showing the driving mechanism and its supporting bracket unsectioned, and Fig. 7 is a perspective view of the bracket that supports the driving mechanism in the modified form of the invention.

2

Describing, by the use of reference characters, first that form of the invention illustrated in Figs. 1 to 4, 1 designates a receptacle to which liquid fuel is supplied through a conduit 2 from a suitable source (not shown). Admission of the liquid fuel to the receptacle is controlled by a valve 5 that is seated to shut off the flow by a float 6 when the float is lifted by an accumulation of liquid fuel in the receptacle to the level indicated by the dot-and-dash line a. The float is fixed to an arm 7 that is pivoted on a pin 8, supported by a bracket 9, and the end of the arm remote from the float bears on the head 10 of the valve 5, between which head, and a tubular guide 11 in which the valve reciprocates, is a helical spring 12 that surrounds the valve and tends to lift the same from its seat.

Rising from the bottom wall of the receptacle 1 is an outlet tube 15, the overflow edge 16 of which is a substantial distance above the liquid level a. The outlet tube 15 is suitably connected to a conduit 17 that constitutes a part of the connections between the liquid dispensing means and the burner, and which will hereinafter be described. 20 Surrounding the upper portion of the outlet tube 15 is a bucket, designated generally by the reference numeral 20, comprising a cylindrical peripheral wall 21, an annular bottom wall 22 that has a sliding fit on the tube 15, and a top wall 23. As a convenient way of attaching the parts of this assembly together, the walls 22 and 23 have circumferential grooves into which the surrounding portions of the peripheral wall 21 are depressed, as indicated at 24 and 25. The peripheral wall 21 has an opening which provides along its lower edge an overflow lip 27. Connected to the top wall 23, desirably by having its lower end reduced and fitted through an aperture in said wall and upset therebeyond, is a rod 30 that is guided within an aperture of a disk 31 suitably mounted within an opening of a cover 32 that closes the top of the receptacle 1 and is shown as secured to the receptacle by screws 33.

Mounted on the end of the cover 32 nearest the disk 31, and secured to the cover by screws 34, is a support or post 35, shown as of channel formation, and desirably constructed of sheet metal. Extending through aligned apertures in the side flanges of the support or post 35, near the top thereof, is a pin 36 on which is pivotally supported an arm 38, shown in perspective in Fig. 4. This arm, also, is preferably constructed of sheet metal and for the reception of said pin 36 its body portion has an aperture 39 that is in axial alignment 50 with a similar aperture for the same purpose in

an integral part 40 that is disposed in a plane parallel to that of the body portion of the arm and is connected to said portion by a horizontal part 41. Said part 41 is provided with a threaded aperture 42. Extended through and free to rotate in an unthreaded aperture in the top 44 of the support or post 35 is an adjusting screw 45 that is threadedly engaged within the previously mentioned aperture 42, so that by turning said screw the arm 38 may be swung on the pin 36. A locking plate 47 is secured to the top of the support or post by a screw 48, and said plate has an aperture somewhat smaller than the head of the screw 45 through which said head partially projects. By tightening the screw 48 and thus depressing the locking plate, the screw 45 may be held against accidental turning or lifting. The edge of the horizontal part 41 beneath the screw 48 is notched to prevent interference with said screw.

Driving mechanism, indicated generally by the reference numeral 50, and including an electric motor 51 of the clock type, is supported by the arm 38. The connection between the mechanism and arm is conveniently made by means of screws 53 that are projected through holes in marginal lugs of the front plate 54 of said mechanism and are screwed into threaded holes in a cross bar 55, the portions of the screws 53 between said lugs and the cross bar occupying notches 56 in the top edge of the arm 38, the screws being turned up tightly to clamp the arm between the front plate 54 and the cross bar 55. Fastened to the driving shaft 58 of the mechanism 50, by means of a screw 59, is a crank 60, on the pin 61 of which is pivoted one end of a link 62, the opposite end of which is similarly connected to the upper end of the rod 30.

The electric motor 51 is connected in the customary way through wires (not shown) with a source of current, and when the motor is energized, the shaft 58 and consequently the crank 60 will be rotated and will, through the connections provided by the link 62 and the rod 30, reciprocate the bucket 20 along the outlet tube 15. When the bucket descends sufficiently to dispose its overflow lip 27 below the liquid level a , the bucket will fill to said level, and then as the bucket ascends all liquid therein, below the plane of the overflow lip 27, will be retained. Now as the bucket approaches the upper end of its stroke and the lip 27 rises above the plane of the overflow edge 16 of the outlet tube 15, the quantity of liquid above said edge will spill over into the outlet tube, the amount depending upon the distance the lip 27 rises above the plane of the overflow edge of the tube. This quantity may be altered, according to the illustrated embodiments, by changing the elevation of the driving mechanism 50 which, in the form now under consideration, is accomplished by turning the screw 45, thereby to swing the arm 38 on the pin 36. The screw 45 is held against lifting, and in any position of adjustment against accidental turning, by the locking plate 47, as previously mentioned.

It is readily apparent from the foregoing that my invention provides a simple and efficient means for volumetrically feeding liquid, which is especially suited to the supplying of liquid fuel in measured amounts to combustion apparatus, the adjustment above described providing very accurate measurement of the quantity of liquid fed at each reciprocation of the bucket.

In the form of the invention illustrated in Figs.

5 to 7, the driving mechanism 65 is supported by a bracket 66 including a split sleeve-like portion 67 that embraces and is slidable on a tubular support or post 68 that is fastened to and rises from the cover 69 of a receptacle 70. The vertical edge of the split sleeve-like portion 67 is turned inwardly to provide a flange 71 that operates in a slot 72 of the post or support 68. The inner edge of the flange 71 is substantially flush with the inner surface of the post or support 68 excepting at its upper end where said flange is increased in width to provide a lug 74 that extends across the bore of the tubular post or support. A compression spring 75 occupies said bore and at its lower end rests upon an abutment 76 which, in the present case, consists of a pin that is projected through aligned holes in the opposite sides of the post. At its upper end the post is internally threaded for the reception of an adjusting screw 78, against the inner end of which the lug 74 is urged by the spring 75, thereby to maintain the bracket 66 in the highest position permitted by the screw 78.

Fastened to the driving shaft 80 of the mechanism 65 is a crank 81 to the pin 82 of which is pivoted the upper end of a link 83. The lower end of said link is similarly connected to a rod 84 that is guided through a central aperture in a disk 85, mounted within an opening of the cover 69. The lower end of the rod 84 is connected to the top 86 of a bucket designated generally by the reference numeral 87. The peripheral wall 88 of said bucket has one or more openings 89, each providing adjacent its lower side an overflow lip 90. Slidably fitting a central aperture in the bottom wall 91 of the bucket is an overflow tube 92, which has its overflow edge 93 a substantial distance above the liquid level b in the receptacle 70, said level being maintained by a float 95, the arm 96 of which is pivoted on a pin 97 supported by a bracket 98, the end of the arm remote from the float bearing on the head of a valve 99 which controls the admission of the liquid to the receptacle 70, supplied from a suitable source (not shown) through a tube 100. The valve is lifted from its seat by a spring 101 that surrounds the valve and is interposed between the head of the valve and the top of a guide 102 in which the valve reciprocates.

Applicable to both forms of the invention above described, but illustrated only in conjunction with the first form as it appears in Fig. 1 of the drawings, are connections between the liquid dispensing device or means and the burner that include a flow retarder, the function of which is to render substantially continuous or constant the flow of liquid fuel to the burner for pilot fire purposes.

In Fig. 1, the burner is designated 105, the same being indicated as a burner of the pot or bowl type, and only a fragment of which is shown. Fuel is supplied to the burner through a conduit 106, to the end of which remote from the burner is connected a tubular fitting 107. The fitting is reduced in diameter at one end to provide a radial shoulder 108 and an adjacent cylindrical part formed with a circumferential groove 109. Ports 110 establish communication between said groove and the bore 111 of the fitting. The reduced end of the fitting beyond said cylindrical part is threaded for the application of a cap 112.

115 designates a flow retarder in the form of a coil of tubing of relatively small diameter, the inlet end of which has connection with the previ-

ously mentioned conduit 17. The outlet end of the coil extends radially through an annular member or ring 117 that encircles the reduced cylindrical part of the fitting 107 and is clamped against the shoulder 108 by the cap 112. Thus, communicative connections are made between the conduits 17 and 106. By reason of the relatively small diameter of the tubing comprising the retarder 115, together with the length and disposition of the same, the liquid that is intermittently discharged from the bucket 20 into the outlet tube 15 is held back or retarded in its flow to such an extent that the discharge of the same into the burner is substantially continuous or constant, avoiding, during operation of the pilot fire, what would otherwise be a noticeably fluctuating flame.

As will be understood by those familiar with liquid fuel burning apparatus of the class herein referred to, fuel for high fire purposes is usually delivered to the burner through the same conduit as that which supplies fuel for pilot fire purposes. Such an arrangement, in practice, is desirably employed with the present invention, but since the invention is concerned only with the feeding of fuel for pilot fire, I have omitted the means for supplying the burner with fuel for higher fire. An arrangement for the latter purpose may follow, for example, that disclosed in the above mentioned Patent 2,247,689 wherein the thermostatically actuated valves that control the fuel feed for high fire purposes are built into the float chamber, which corresponds substantially to the receptacle 1 (or 70) of the present case. In a construction wherein the high fire valve is enclosed in the same receptacle with the bucket feed which supplies fuel for pilot fire purposes, the flow retarder 115 may be situated inside the receptacle with its inlet end communicating with the outlet tube of the bucket feed (tube 15 of Fig. 1, for example) and its opposite end with the outlet side of the high fire valve, from which point on the fuel conveying means serves to deliver the fuel for both pilot and high fire. Obviously, in such a case, the outlet tube of the bucket feed would terminate adjacent the bottom of the receptacle and be closed below its point of communication with the retarder.

Having thus described my invention, what I claim is:

1. For use in liquid dispensing means including a barrier having an overflow edge defining the outlet of said means, and liquid transfer means in sliding contact with the barrier and having a liquid chamber of which said barrier constitutes a wall, the transfer means being reciprocable between a low liquid receiving position and a high liquid discharging position in the latter of which positions said chamber extends above said overflow edge; a support, a structure pivotally connected to said support for swinging movement on a substantially horizontal axis, a screw providing an adjustment between the support and structure and by one of which said screw is sustained for rotary and non-reciprocatory movement and with the other of which it has threaded connection whereby, upon the turning of said screw, the structure is swung in a vertical direction with respect to the support, unitary driving mechanism including a prime mover mounted on said structure for reciprocating the transfer means, and operative connections between said mechanism and the transfer means and by which the transfer means is supported.

2. For use in liquid dispensing means including a barrier having an overflow edge defining the outlet of said means, and liquid transfer means in sliding contact with the barrier and having a liquid chamber of which said barrier constitutes a wall, the transfer means being reciprocable between a low liquid receiving position and a high liquid discharging position in the latter of which

positions said chamber extends above said overflow edge; a support, a structure pivotally connected to said support for swinging movement on a substantially horizontal axis, a screw providing an adjustment between the support and structure and by one of which said screw is sustained for rotary and non-reciprocatory movement and with the other of which it has threaded connection whereby, upon the turning of said screw, the structure is swung in a vertical direction with respect to the support, unitary driving mechanism including a prime mover mounted on said structure for reciprocating the transfer means, and operative connections between said mechanism and the transfer means and by which the transfer means is supported.

3. For use in liquid dispensing means including a barrier having an overflow edge defining the outlet of said means, and liquid transfer means in sliding contact with the barrier and having a liquid chamber of which said barrier constitutes a wall, the transfer means being reciprocable between a low liquid receiving position and a high liquid discharging position in the latter of which positions said chamber extends above said overflow edge; a support, a structure pivotally connected to said support for swinging movement on a substantially horizontal axis, the support and said structure having apertures in vertical axial alignment, a screw freely rotatable within the aperture of the support and threadedly engaged within the aperture of a structure whereby the turning of said screw adjusts the structure in a vertical direction, unitary driving mechanism including a prime mover mounted on said structure for reciprocating the transfer means, and operative connections between said mechanism and the transfer means and by which the transfer means is supported.

4. For use in liquid dispensing means including a barrier having an overflow edge defining the outlet of said means, and liquid transfer means in sliding contact with the barrier and having a liquid chamber of which said barrier constitutes a wall, the transfer means being reciprocable between a low liquid receiving position and a high liquid discharging position in the latter of which positions said chamber extends above said overflow edge; a support, a bracket slidable vertically on the support, adjusting means for varying the elevation of the bracket with respect to the support, unitary driving mechanism including a prime mover mounted on said bracket for reciprocating the transfer means, and operative connections between said mechanism and the transfer means and by which the transfer means is supported.

5. For use in liquid dispensing means including a barrier having an overflow edge defining the outlet of said means, and liquid transfer means in sliding contact with the barrier and having a liquid chamber of which said barrier constitutes a wall, the transfer means being reciprocable between a low liquid receiving position and a high liquid discharging position in the latter of which positions said chamber extends above said overflow edge; a support, a bracket slidable vertically thereon, a spring tending to elevate the bracket, an adjusting screw having threaded engagement with the support and bearing upon an abutment portion of the bracket and by which the bracket may be depressed and held in depressed position in opposition to said spring, unitary driving mechanism including a prime mover mounted on said bracket for reciprocating the transfer means,

and operative connections between said mechanism and the transfer means and by which the transfer means is supported.

6. For use in liquid dispensing means including a vertically arranged tube having an overflow edge defining the outlet of said means, and a bucket surrounding and slideable on said tube, the bucket being provided with a rod which rises from the bucket substantially in axial alignment with the tube; a guide through which said rod is reciprocable and by which it is maintained vertical, a support adjacent said guide, a structure sustained by the support above the guide, means for adjusting the structure vertically of the support, driving mechanism mounted on said structure for reciprocating the bucket, said mechanism including a crank action, and operative connections between the crank action and said rod through which, and the rod, said bucket is supported.

7. In combination, a volumetric liquid feeding device that functions to intermittently dispense relatively small amounts of liquid, and an unobstructed, valveless liquid conveying means of a constant flow capacity through which the liquid flows by gravity from said device to a point of discharge, said conveying means including a flow retarder consisting of a substantially horizontally disposed coil of tubing that forms a part of said conveying means, the tubing being of sub-

stantially smaller cross sectional area than the remainder of said means, an annular member to which one end of the coil is connected so that the coil communicates with the interior of said member, a fitting incorporated in the conveying means, said fitting having an end reduced to provide a substantially radial shoulder, and a cylindrical part adjacent said shoulder, the fitting being threaded beyond said cylindrical part, said annular member encircling said cylindrical part, and means engaged with the threaded portion of the fitting to clamp said member against the shoulder, said member and the cylindrical part of the fitting being shaped to provide a circumferential channel, the fitting having a bore and a port through which the bore and said channel communicate.
